PORTABLE COOKING GRILL

Jim R. Grafton, 1112 34th Ave., Moline, Ill. 61265;
Glenn E. Wilkins, 3722 Forrest Road, Davenport, Iowa
52804; and Joseph F. Murphy, 1106 25th Avenue
Court, Moline, Ill. 61265

Filed Feb. 25, 1971, Ser. No. 119,071

Term of patent 14 years

Int. Cl. D7—02

U.S. Cl. D81—10 G

FIG. 1

FIG. 2

FIG. 3

FIG. 1 is a perspective view of the portable cooking grill.

FIG. 2 is a top plan view of the grill, the bottom view being substantially identical to the top view.

FIG. 3 is a view of one side of the grill, the opposite side view being substantially identical except for the two holes in the one side which do not appear in the opposite side.

We claim:

The ornamental design for a portable cooking grill, substantially as shown and described.
